UNITED STATES PATENT OFFICE.

ARTHUR ROBITAILLE, OF PUTNAM, CONNECTICUT.

AUTOMATIC CONTROLLED LIQUID-FUEL BURNER MECHANISM.

Application filed September 16, 1925. Serial No. 56,735.

To all whom it may concern:

Be it known that I, ARTHUR ROBITAILLE, a citizen of the United States, residing at Putnam, in the county of Windham and State of Connecticut, have invented certain new and useful Improvements in Automatic Controlled Liquid-Fuel Burner Mechanism, of which the following is a specification.

This invention relates to automatic controlled liquid fuel burner mechanism designed primarily for use in connection with hot water heaters or boilers, but it is to be understood that a burner in accordance with this invention, can be employed for any purposes for which it is found applicable, and the invention has for its primary object to provide, in a manner as hereinafter set forth, a burner mechanism of the class referred to for producing and regulating combustion and heat with respect to a water heater or boiler.

The invention further aims to provide, in a manner as hereinafter set forth first, a burner where combustion of liquid fuel or the vapor therefrom is produced; second, regulation of the point of combustion to secure an economical conduction of heat to the water; third, automatically regulating or controlling of the liquid fuel supply, thus controlling the heat generated and imparted to the water; and fourth, for cutting off the liquid fuel supply in case of failure of combustion.

Further objects of the invention are to provide, in a manner as hereinafter set forth, an automatically controlled liquid fuel burner which is comparatively simple in its construction and arrangement, durable, thoroughly efficient in its use, readily installed, and comparatively inexpensive to set up.

With the foregoing and other objects in view, the invention consists of the novel construction, combination and arrangement of parts, as hereinafter more specifically described and illustrated in the accompanying drawings, wherein is shown an embodiment of the invention, but it is to be understood that changes, variations and modifications can be resorted to which fall within the scope of the claim hereunto appended.

In the drawings wherein like reference characters denote corresponding parts throughout the several views:

Figure 1 is an elevation of a hot water boiler showing the adaptation therewith of

an automatically controlled liquid fuel burner mechanism in accordance with this invention.

Figure 2 is a sectional elevation, illustrating the boiler with the mechanism, in accordance with this invention, arranged therewith.

Figure 3 is a top plan view of the burner mechanism attached to the boiler.

Figure 4 is a section on line 4—4, Figure 3.

Figure 5 is a fragmentary view, in elevation of the controllable liquid fuel feeding valve.

Figure 6 is a detail illustrating the controlling switch for the motor circuit.

Referring to the drawings in detail, 1 denotes a hot water boiler and 2 the fire box thereof. The boiler 1 has arranged at the top thereof a thermostatic controlling device 3 for a liquid fuel feed valve to be presently referred to.

The burner element of the automatically controlled liquid fuel burner mechanism, in accordance with this invention, is generally indicated by the reference character 4 and it consists of a tubular or cylindrical body portion 5, formed with an open top and an integral bottom 6 having a depending portion 7 forming a directing means for the liquid fuel not consumed. The bottom 6 is provided with a depending socket forming member 8 for the reception of the vertical standard 9 of a support 10. The body portion 4 is positioned within the fire box 2 at the bottom thereof and extends a substantial distance upwardly within said fire box 2. Formed integral with one side of the body portion 5, as well as extending thereinto, is a hollow elbow shaped member 11, having the lower part of that portion arranged within the body portion 5 of concave curvature to provide what may be termed a collecting pan as indicated at 12.

The burner element 4 further includes a dome shaped cover 13 which is seated upon and overlaps the top of the body portion 5. The cover 13 is formed with a substantially enlarged opening 14 providing an outlet for the products of combustion from the combustion chamber 15 formed by the burner element 4.

The body portion 5 directly above and in close proximity to the depending portion 7 of the bottom 6 is formed with an opening 16 in which is secured one end of the liquid

fuel return pipe 17. The outer portion of the member 11 depends with respect to the body portion 4 and has extending therein, as well as connected therewith, a blast or air conducting pipe 18 which leads from a blower 19 mounted on the support 20. The blower 19 is operated from an electric motor 21 having its operation controlled by an actuating mechanism for the liquid fuel supply shut off valve.

The liquid fuel supply pipe, which leads from a suitable source of supply, is indicated at 22 and opens into a controllable feed valve mechanism indicated generally 15 by the reference character 23. Extending from the valve mechanism 23 to a liquid fuel cut off valve mechanism, referred to generally by the reference character 24, is a liquid fuel conducting pipe 20 25, and extending from the mechanism 24, into the pipe 18 and up into the upper portion of the member 11 is a liquid fuel feed pipe 26. The upper portion of the member 11 is what may be termed a burner nozzle 25 and the upper portion of the pipe 26 is what may be termed a liquid fuel discharging nozzle and is indicated at 27 and extends partly across the pan 12.

The stem of the feed valve mechanism is 30 indicated at 28, projects from the casing of said mechanism 23, and supports a dial plate 29, and with the dial on the plate 29 is associated a pointer 30, formed on the inner end of an actuating arm 31 connected to the stem 28. The arm 31 is counterbalanced as at 32 and is connected by a pulling member 33, in the form of a chain to the thermostatic controlling device 3.

The stem of the cutoff valve mechanism 40 24 for the liquid fuel is indicated at 34, is spring controlled and projects from one end of the housing of said mechanism 24 and is disposed at right angles with respect to the conducting pipe 25. Overhanging that end 45 of the housing 35 from which the stem 34 projects is an arm 36, to which is pivotally connected, as at 37, a depending link 38 which normally bears against the stem 36 for the purpose of maintaining the valve mechanism 24 open. Pivotally connected, as at 39, to the lower end of the link 38 is one end of a lever arm 40, which in proximity to its other end is pivotally connected, as at 41, to a link 42. Depending from the housing 55 35 is a lug 43, to which the inner end of the link 42 is pivotally connected, as at 44. The link 42 carries an adjusting screw 45 for controlling its movement in a direction towards the housing 35. The lever 40 extends from 60 the outer end of the link 42 and is formed with a hook-shaped free end 46 for suspending the bale 47 of a collecting receptacle 48. The receptacle 48 is arranged in a manner so that the discharge end of a pipe 17 will 65 extend thereover and discharge therein a

liquid fuel conducted by the pipe 17 from the chamber 15, and by this arrangement as the body of fuel increases in the receptacle 48, the weight thereof will swing the lever 40 from the full line to the dotted line position shown in Figure 4, whereby the valve stem 34 will be released and move in a direction to close the valve mechanism 24, thereby shutting off the supply of fuel.

Means is employed for opening the motor 75 driving circuit when the feed valve mechanism is closed, and said means consists of a switch device 49, in the motor circuit, and which is operated by a flexible member 50 extended from the pulling member 33, 80 whereby the switch device will be controlled by the thermostatic device 3. The switch device 49 can be of any suitable form.

The burner element is started by igniting a small quantity of kerosene within the pan 85 12. The cutoff valve is opened and the collector 42 suspended from the actuating mechanism and on the opening of the cutoff valve the motor 21 is thrown into operation. Prior to the opening of the cutoff valve the feed valve is opened to the desired extent and which can be ascertained from the dial. The fuel travels through the pipes 23, 25, and 26 and drops into the pan or cup 12 where it is vaporized by the heat and blown by the 95 blast into the burner element where combustion takes place. The feed of the oil can be regulated by adjustment of the pointer 30 relative to the dial on the plate 29 and furthermore can be also regulated by the thermostatic controlling device 3, which can be a damper regulator or a temperature regulator. The device 3 acts to close the feed valve with respect to the temperature of the water. In case the flame at the burner 100 element is extinguished and the fuel continues to be supplied to such element, it will flow through the return pipe 17 to the collector 42, and the weight of the fuel within the collector 42 will operate the actuating 110 mechanism for the cutoff valve, close the latter.

It is thought that the many advantages of an automatic controlled liquid fuel burner mechanism in accordance with this invention can be readily understood, and although the preferred embodiment of the invention is as described and claimed, yet it is to be understood that changes in the details of construction can be had which will fall within the scope of the invention as claimed.

What I claim is:

In a liquid fuel burner mechanism an open top receptacle including a body portion and a bottom forming a combustion chamber, said body portion at one side thereof formed with an opening near said bottom, said bottom having one side thereof provided with a depending portion for directing liquid fuel to said opening for the discharge of such 130

fuel, a casting forming an inlet for said chamber common to liquid fuel and a blast of air and formed of a pair of arms, one of the arms of said casting integral with and 5 extending through the other side of said body portion and into said chamber, the inner end of such arm having its lower portion offset to provide a depending liquid fuel collecting cup, the other arm of said 10 casting integral with said body portion, a

closure for the top of said body portion and formed with a central opening and a liquid fuel feed pipe extending through said last mentioned arm and partly through the first mentioned arm, that part of the feed pipe in 15 said horizontal arm extending partly across said cup.

In testimony whereof, I affix my signature hereto.

ARTHUR ROBITAILLE.
